UNITED STATES PATENT OFFICE

EUGEN KLEIN, OF DRESDEN, GERMANY

APPLIANCE FOR AUTOMATICALLY REGULATING THE ENTRANCE OF FABRICS OR WEBS
INTO LAPPING MACHINES

Application filed December 20, 1927, Serial No. 241,350, and in Germany December 23, 1926.

The present invention has for its object an appliance for the automatic regulation of the entrance of the fabric or web into lapping-machines. The novelty of the appliance mentioned consists in that for an exact introduction of the fabric or web to be lapped and for an accurate position of the two layers or edges of the fabric or web to each other one or more feelers or touch-levers resting against each 5 of the layers or edges of the fabric or web, is or are arranged on a carriage automatically geared and known per se. These feelers or touch-levers are connected pneumatically or electromagnetically to pairs of relays and are 10 connected by said relays with a driving-device provided for the reciprocating carriage and with another driving-device operating the lapping-appliance in such a manner that in the case of slipping of the fabric 15 or web-edges relatively to each other the mutual play of the feelers or touch-levers actuates the driving-appliance for the lapping-device, whereas in case of slipping of the fabric or web caused by the variation in the 20 width of the fabric or web, said levers actuate the driving appliance arranged for the carriage.

In this manner the advantage is obtained 25 that the edges of the fabric or web are laid vertically above one another and the feeding of the lapped fabric or web is adjusted, notwithstanding the varying width of the fabric or web, in lapping machines, viz: in machines into which the fabric or web is fed wide, 30 in which it is lapped i. e. folded together.

An example of a form of construction of the appliance arranged according to the present invention is shown in the drawings annexed, in which

40 Fig. 1 is a vertical section of the lapping-device according to the line A—B, Fig. 4, parallel to the face of the fabric or web running towards the staple-device,

45 Fig. 2 a horizontal section according to line C—D of Fig. 1, laid through the feeling-apparatus.

Fig. 3 a horizontal section according to line E—F of Fig. 1, laid along the adjusting-bars of the lapping device.

50 Fig. 4 a vertical section to the line G—H of

Fig. 1 laid perpendicular to the fabric or web, Fig. 5 a vertical section through a feeling-apparatus provided with electrical gearing-contacts,

55 Fig. 6 a plan and partial horizontal section through a driving-appliance arranged as an electric friction-clutch for reversing both adjusting movements,

Fig. 7 a switch-plan of the total electric gearing plant,

60 Fig. 7^a a detail horizontal section, on an enlarged scale, of the feeling apparatus and adjacent parts shown in Fig. 7,

65 Fig. 8 a second form of construction of the appliance in a horizontal section partly laid along the lapping-bars and partly through the feeling-apparatus situated below said bars, the parts mentioned being in the position taken by them in the moment of the introduction of the command for displaying 70 the lapping bars,

75 Fig. 9 a similar section with the position of the parts taken after the automatic finish of the displacement of the lapping-bars introduced after the command, and

80 Figs. 10 and 11 a modified form of construction of a feeling-apparatus provided with feeling-levers known per se and swinging in the direction of the run of the fabric or web.

85 As seen in the drawing, Figs. 1 to 4, the fabric or web 1 is drawn by the staple-device arranged in the lower part of the machine, and omitted in the drawing, into the upper part of the lapping-appliance in the direction of the arrow 2, hereafter the fabric or web is broken in its middle part by the angular face 3 and then lapped or plied together by the two adjusting-bars 4. In this state the fabric or web runs through the two pairs of rolls 5, 5 and 6, 6 and reaches the staple-device. The 90 feeling-apparatus 7 is inserted between the two pairs of rollers 5, 5 and 6, 6 in such a manner that each of the two edges of the fabric or web passes through a slot 8 and 9 respectively arranged in the apparatus and actuating each of the feeling-levers 10 and 11 respectively. Each of said levers swings in a plane perpendicular to the face of the fabric or web, whereas the fabric or web is simultaneously supported by the sliding-planes 12 95

and 13 respectively arranged within the feeling-apparatus 7, for the purpose of preventing the deviation of the fabric or web.

The adjusting forces freed by the feeling-levers 10 and 11 are transmitted across the movable cable 14 to the relays to be described hereinafter, said cable containing the electric wires. The command given by the feeling-levers is sent from the relays to the driving-devices 15 and 16 to be described hereinafter and causing the displacement of the adjusting bars 4 or the feeling-apparatus 7. Said adjusting bars may for this purpose be arranged for instance in a slide 17 connected with the rod 18 actuated by the driving-device 15. The feeling apparatus 7 is advantageously arranged with four rolls running between four guide bars 19 and displaced by the driving-device 16 by means of the wire-ropes or chains 20.

For the purpose of easily inserting the feeling-apparatus 7 into the width of the fabric or web it is of advantage to reduce the width of the sliding-faces 12, 13 to a bevelled guide-tongue 21, deeply projecting into the fabric or web.

The swing-movements of the feeling-levers 10, 11 of the feeling-apparatus 7 are used for producing the regulating impulses; in case the latter are electric currents, it is only necessary to provide the feeling-levers according to the shape shown in Fig. 5 with contacts 22, 23 respectively, which are opened or closed during the swinging-movement of the feeling-levers. According to Fig. 5, it is assumed for instance that the edge 24 of the fabric or web moves backwards and does not contact with the feeling-lever 10, whereas the other edge 25 of the fabric or web is situated within the plane of the drawing and moves back with the feeling-lever 11. Therefore the pair of contacts 22 remains closed by the power of the coiled spring 28, whereas the pair of contacts 23 positively opens itself contrary to the power of the coiled spring 29. The tension of the coiled springs 28, 29 can be regulated by the screws 30 and 31 whereas the precise adjustment of the pairs of contacts is ensured by the screws 26, 27.

If the driving-devices 15, 16 mentioned above are also to be moved by electricity, they can be arranged as auxiliary motors rotating in two directions or as attracting magnets acting on the moving bars 18 and 20. However, electro-mechanisms, arranged in such a manner that they act onto a source of energy only in a disengaging manner, work with lower regulating currents, while simultaneously excluding noxious mass-effects.

The form of construction of such a driving-device acting according to the principle of the known friction reversing clutches is represented in Fig. 6.

The shaft 33 of each reversing clutch is driven by any suitable shaft of the machine by

means of a rope 32; in Fig. 7 the ropes 32 of the reversing clutches 15, 16 may be connected and actuated by a single shaft or they may be connected to separate shafts of the machine. The magnet-casing 35 of the electric clutch is fastened to said shaft 33 carrying also the wheel 37 engaging with another wheel 38 which rotates the magnet-casing 36 fastened to the shaft 34 of a similar clutch in an inverse direction. If a current is supplied to the slip-rings 39 or 40 by brush-collectors not shown and the coil 41 or 42 is excited thereby, the armature-disc 43 or 44 rotatably arranged on the shaft 33 or 34 is magnetically attracted and engaged by friction-force with the magnet-casing 35 or 36; said disc partakes together with the small wheel 45 or 46 connected with it of the rotations of the shaft 33 or 34. The wheel 47 engaging the small wheel 45 or 46 is therefore according to the excitation of the one or other clutch rotated in a right-hand or left-hand direction; simultaneously the small wheel 49 connected with the said wheel 47 by the shaft 48 is rotated. Said rotary movements are transformed into regulating and fro movements by the engagement of the wheel 49 with the rod 18 shaped as a rack. The same movement can be given to a chain, in case the small wheel 49 is replaced by a chain wheel.

For completing the regulating-arrangement two pairs of relays 50, 51 and 52, 53 are still provided which are joined together on a switch board 54 and can be inspected on the plan of the latter, Fig. 7. The four relays are of same arrangement and each of them is provided with a contact *a*, which remains closed in case the relay-coil *s* is without current but is opened if the coil *s* is put under current. Furthermore, a contact *b* is provided for each relay, said contact being closed by the contact *c* in case the coil *s* is under current, but opened if the coil *s* is without current.

The coils *s* of the pair of relays 50, 51 are so switched that they are both supplied with current by the contact 22 of the feeling-apparatus 7, as long as the feeling-lever 10 engages the edge of the fabric or web, said coil-current being however disconnected, if the lever 10 is moved away from its support by the edge of the fabric or web and is swung outwardly. The same can also be said of the coils *s* of the pair of relays 52, 53; both coils are under current until the feeling-lever 11 engages the edge of the fabric or web, but they are without any current as soon as the feeling-lever 11 swings outwardly and thereby opens the contact 23.

Furthermore the contacts *a* and *b* of the relays 50 and 52 are connected with the two coils *n* and *m* of the electric reversing-clutch 15 in such a manner that the coil *n* of the latter is excited if the contact *b* of the relay 50 and the contact *a* of the relay 52 are closed, whereas said coil *n* remains without current.

if one of said contacts *a* and *b* connected in series is opened. On the other hand, the second clutch-coil *m* is excited, in case the contact *a* of the relay 50 and the contact *b* of the relay 52 are closed. In case one of these contacts *a* or *b* connected in series remains in its open position, the coil *m* is without current.

In contradistinction to this, the contacts *a* and *b* of the relays 51 and 53 are connected with the two coils *q* and *r* of the reversing-clutch 16 in such a manner that the coil *q* is under current if both contacts *a* are closed and the coil *r* is under current if both contacts are closed. In case, however, one of the contacts *a* is opened the coil *q* is without current and if one of the contacts *b* is opened, the coil *r* is without current.

In consequence of the foregoing arrangement the following will result:

1. As soon as the feeling-lever 10 remains at rest on the edge of the fabric or web and the feeling-lever 11 simultaneously swings out the coil *n* of the reversing-clutch 15 is excited, whereas the coil *m* of the same clutch and the coils *q* and *r* of the reversing-clutch 16 remain without current.

2. If the feeling-lever 11 remains at rest on the edge of the fabric or web, whereas the feeling-lever 10 swings simultaneously out, only the coil *m* of the reversing-clutch 15 is excited and the coil *n* of the same clutch and the coils *q* and *r* of the reversing-clutch 16 are without current.

3. If both feeling-levers 10 and 11 are at rest the two coils *n*, *m* of the reversing-clutch 15 and the coil *q* of the reversing-clutch 16 remain also without current; however the coil *r* of the clutch last mentioned is put under current.

4. If both feeling-levers 10, 11 are swung out again both coils *n*, *m* of the reversing-clutch 15 as well as the coils *r* of the clutch 16 remain without current, however the coil *q* of the clutch 16 is put under circuit.

It follows from this that, in case of an accurate adjustment of the rope 32 in the sense of rotation, it is possible to make use of the reversing-clutch 15 for regulating the lapping procedure by the rod 18 and the adjusting bars 4 and of the reversing-clutch 16 for regulating the feed of the feeling-apparatus 7 by the rope or chain 20.

During the time the edges of the fabric or web precisely face each other, the feeling-apparatus 7 will swing out with a small amplitude, so that the feeling-levers 10, 11 will simultaneously and periodically open and close the contacts 22 and 23. However, as soon as the edges of the fabric or web will recede owing to an unequal width of the fabric or web, the feeling-apparatus will follow until the feeling-levers again reach the edge of the fabric or web, whereupon the swinging movement of the feeling-apparatus will begin again.

The two different regulations caused by the driving-devices 15 and 16 cannot mutually disturb each other for the reason that they cannot work simultaneously owing to their peculiar switching described above, but only one after another. If the edges of the fabric or web do not precisely cover each other, for instance in case of the feeling-levers being pressed outwards on both sides, the feeling-apparatus will only follow until the first edge of the fabric or web is passed over, whereupon in addition thereto the drive-device 15 seeks to place the edges of the fabric or web exactly above another; only at the moment when both feeling-levers are simultaneously pushed off or simultaneously freed the drive-device 16 begins to work again.

With fabrics or webs the edges of which show lateral deviations on a changing tension of the fabric or web, and especially in its slack condition, there is danger of a wrong regulation. In this case it is preferable to insert a contact-device 56, driven by the main shaft 55 of the machine, into the regulating circuit, said contact-device periodically and automatically interrupting or opening the regulating current in the moments when the fabric or web tension relaxes during the procedure of piling up.

Owing to the fact that during each complete turn of the main shaft 55 the tension of the fabric or web relaxes, according to the work, twice immediately after the return of the folding apparatus, therefor periodically, the contact-apparatus 56 may be constructed for instance of insulating material enclosing two interconnected contact pieces which during one turn or rotation of the main-shaft 55 within the same period twice close and open the regulating-current at two slip-springs arranged opposite each other. The opening of the circuit has, each time, the effect that the coils of the drive-device 15 or 16 become currentless and their regulating-movements will cease whilst the "break" continues. In this manner wrong regulations are excluded.

For the same reason said device will also be provided in the case in which the fabric or web is taken up by a winding-apparatus arranged with flat reel.

The automatically working lapping-machine described above can, according to its purpose, be arranged not only to all kinds of folding-machines working with a piling-apparatus, but also to winding machines and machines inserting press-boards into the fabric or web, as well as similar finishing machines.

In the above described appliance the command for the displacement of the lapping-bars is annulled by the edges of the fabric or web being in contact with the feeling-levers and returning again to their right position. However, the path of the edges of

the fabric or web cannot instantaneously follow the displacement of the lapping bars, for which a certain time will be necessary. Consequently the lapping bars are automatically displaced for a distance longer than that corresponding to the deviation of the edges of the fabric or web at that time and in consequence a super-regulation and pendulum phenomena will take place.

10 This drawback can be removed by annulling the command not only by correcting the path of the fabric or web in a right manner, but by deriving and beginning it by a displacement of the feeling-levers, said displacement being introduced transversely to the edge of the fabric or web and dependent on the movement of the lapping-bars themselves.

15 In this manner the advantage is obtained that the displacement of the lapping-bars is adjusted in proportion to the deviation of the edges of the fabric or web to be corrected and on exceeding said displacement, for instance in consequence of the inertia of the moved mass, the reversal of the command will 20 take place at once.

25 Instead of displacing the feeling-levers themselves those members acted upon by said levers can also be displaced in an opposite sense so that the same purpose is obtained as 30 by the displacement of the feeling-levers.

As seen from Figs. 8 and 9, the lapping-bars 4 are fastened to a slide 17 movable by the drive-device 15 in the direction of the arrow 60, by means of the rack 18. Said slide 35 17 is provided with lateral teeth engaging the toothed wheels 61, 62 and rotating the latter. Said toothed wheels are fastened to the vertical shafts 63, 64 also carrying the conical wheels 65, which are in engagement 40 with the conical wheels 66 fastened to the shafts 67, 68. The feeling apparatus 7 can, in case of deviations in the width of the fabric or web, be displaced in the direction of the arrow 69 along said two shafts each being 45 provided with a longitudinal groove, whereas the rotary movement of the shafts mentioned is simultaneously and undisturbedly transmitted to the threaded spindles 70, 71 arranged with a key and bored centrally.

50 The rotary movement of the shafts 67, 68 is transformed by the threaded spindles 70, 71 into a reciprocating movement of the guides 72, 73 in which the feeling-levers 10, 11 are yieldingly arranged. In view of the 55 fact that the spindle 70 is lefthand threaded and the spindle 71 righthand threaded, the feeling-levers 10, 11 are displaced in an opposite sense.

The mode of operation of the form of the 60 device shown in Figs. 8 and 9 is as follows:

If, for instance, during the slipping of the edges of the fabric or web, the feeling-lever 11 (Fig. 8) is swung out, whereas the other feeling-lever 10 remains at rest, the driving-device 15 is inserted and the rack 18 together

with the rack 17 together with the lapping-bar 4 is moved in the direction of the arrow 60. The new position of the lapping-bars correcting the run of the fabric or web is represented in Fig. 9. For the purpose mentioned in the introductory part of the description of only maintaining the command for such a long period until the lapping-bars 4 have reached the displacement defined by the smaller or larger deviation of the edges of the fabric or web, the feeling-levers 10, 11 are displaced transversely to the edges of the fabric or web simultaneously with the movement of the lapping-bars, until the lever 11 slides off the edge of fabric or cloth belonging to it and swings back, whereas simultaneously the lever 10 just begins to touch the other edge of fabric or web. Thereby the command is immediately cancelled so that the further displacement of the lapping-bars 4 will also stop. In case of a super-regulation the command is even inverted because then the feeling-lever 10 is brought to swing out by the edge of fabric or web belonging to it, whereas the lever 11 remains at rest. For the same reason a reversal of the command takes place, as soon as the fabric or web begins to again adjust itself correctly. The lapping-bars 4 will therefore return to their middle-position proportionately to the 95 equalization which takes place. The return of the lapping-bars to their middle-position takes place, therefore, not at the moment—as usual up to now—when the fabric or web begins to overrun in the other direction its right position, but immediately after the fabric or web begins to move towards its right position. The danger of overtaxation and an oscillating movement is thereby avoided.

Instead of displacing the feeling-levers, 105 themselves transversely to the edge of the fabric or web the corresponding counter-members, for instance in the electric gearing, the counter-contacts of the pairs of contacts can be displaced for finishing the regulating-procedure. An example of construction for this purpose is represented in Figs. 10 and 11 whereby it is assumed that the feeling-levers 74, 75 do not swing out perpendicularly to the face of the fabric or web but in the direction of the run of the edges of the fabric or web. Fig. 10 shows the manner in which the command is given by opening the pair of contacts 23 and Fig. 11 shows how said command is terminated through a repeated 110 closure of the pair of contacts 23 by moving the counter-contact fastened to the slide 73.

What I claim is:

1. In apparatus for automatically regulating the feeding of fabric or web into lapping 125 machines in order to ensure the correct positioning of the edges of adjacent layers with respect to each other comprising, a movable lapping appliance, a carriage, a feeling lever carried by said carriage in position to en- 130

gage the fabric or web, and means controlled by the movement of said feeling lever for actuating said lapping appliance.

2. An apparatus for automatically regulating the feeding of fabric or web into lapping machines in order to ensure the correct positioning of the edges of adjacent layers with respect to each other comprising, a movable lapping appliance, a carriage, a plurality of 10 feeling levers carried by said carriage and arranged to engage the fabric or web, and means controlled by the movement of said feeling levers for actuating said lapping appliance.

15 3. An apparatus for automatically regulating the feeding of fabric or web into lapping machines in order to ensure the correct positioning of the edges of adjacent layers with respect to each other comprising, a movable lapping appliance, a carriage, a feeling lever 20 carried by said carriage in position to engage the fabric or web, and a reciprocating means controlled by the movement by said feeling lever for actuating said lapping appliance.

25 4. An apparatus for automatically regulating the feeding of fabric or web into lapping machines in order to ensure the correct positioning of the edges of adjacent layers with respect to each other comprising, a movable lapping appliance, a carriage, a plurality of 30 feeling levers carried by said carriage and arranged to engage the fabric or web, and a reciprocating means controlled by the movement by said feeling levers for actuating said 35 lapping appliance.

5. An apparatus for automatically regulating the feeding of fabric or web into lapping machines in order to ensure the correct positioning of the edges of adjacent layers with 40 respect to each other comprising, a movable lapping appliance, a movable carriage, a plurality of feeding levers carried by said carriage and arranged to engage the fabric or web, and mechanism controlled by the movement 45 of said feeling levers for actuating the carriage.

6. An apparatus for automatically regulating the feeding of fabric or web into lapping machines in order to ensure the correct positioning 50 of the edges of adjacent layers with respect to each other comprising, a movable lapping appliance, a movable carriage, a plurality of feeling levers carried by said carriage and arranged to engage the fabric or 55 web, means controlled by the movement of said feeling levers for actuating said lapping appliance, and mechanism controlled by the movement of the feeling levers for actuating the carriage.

60 7. An apparatus for automatically regulating the feeding of fabric or web into lapping machines in order to ensure the correct positioning 65 of the edges of adjacent layers with respect to each other comprising, a movable lapping appliance, a movable carriage, a plu-

rality of feeling levers carried by said carriage and arranged to engage the fabric or web, a reciprocating means controlled by the movement by said feeling levers for actuating said lapping appliance, and mechanism controlled by the movement of the feeling levers for actuating the carriage.

70 8. An apparatus for automatically regulating the feeding of fabric or web into lapping machines in order to ensure the correct positioning of the edges of adjacent layers with respect to each other comprising, a movable lapping appliance, a movable carriage, a plurality of feeling levers carried by said carriage in position to engage the fabric or web, 75 means controlled by the movement of said feeling levers for actuating said lapping appliance, mechanism controlled by the movement of the feeling levers for actuating the carriage, a main driving-shaft, a device driven thereby, said device being arranged to be periodically regulated by the tension of the fabric or web for automatically controlling the movement of the lapping appliance 80 and carriage.

90 9. An apparatus for automatically regulating the feeding of fabric or web into lapping machines in order to ensure the correct positioning of the edges of adjacent layers with respect to each other comprising, a movable lapping appliance, a carriage, a plurality of 95 feeling levers adjustably mounted in said carriage and arranged to engage the fabric or web, and means controlled by the movement of said feeling levers for actuating said lapping appliance.

In testimony, that I claim the foregoing as my invention, I have signed my name this 8th day of December, 1927.
